E. TURGEON

COUCH BED

Filed March 25, 1921

Inventor
Edward Turgeon
By his Attorneys
Paul Paech

UNITED STATES PATENT OFFICE.

EDWARD TURGEON, OF MINNEAPOLIS, MINNESOTA.

COUCH BED.

Application filed March 25, 1921. Serial No. 455,531.

To all whom it may concern:

Be it known that I, EDWARD TURGEON, a citizen of the United States, resident of Minneapolis, in the county of Hennepin and State of Minnesota, have invented certain new and useful Improvements in Couch Beds, of which the following is a specification.

This invention relates to improvements in the type of couches that are designed to be converted into beds of substantially greater width than the main or seat portion of the couch, and the object of the invention is to provide a couch having a main or seat section, a back section, and a front section in which, when the device is to be used as a couch, the back section is locked in a nearly upright position the front section being turned down into a substantially vertical position; in which it is necessary to raise the front section before the back section can be turned down; in which, when the three sections are in a horizontal position, the back and front sections are locked against downward movement, and the back section must be turned up to release the front section and permit it to be turned down into a vertical position.

The invention consists generally in the constructions and combinations hereinafter described and particularly pointed out in the claims.

In the accompanying drawings forming part of this specification,

Figure 1 is a plan view of a couch-bed with movable sections turned into a horizontal position, a part of the bed being broken away,

Figure 2 is a side elevation of the structure shown in Figure 1, looking in the direction of the arrow, the movable front and back sections being shown in dotted lines in the positions they occupy when the device is being used as a couch,

Figure 3 is a detail elevation of a part of the structure shown in Figure 2, looking in the direction of the arrow in said figure.

In the drawings, A represents, as a whole, the main or seat portion of the couch. B represents the back section and C the front section. The main section A is preferably provided with the end rails 2, 2, suitable legs 3, 3, cross bars 4 and longitudinally extending bars 4^a. Suitable braces, such as 6, may also be used to strengthen or stiffen the main section of the device.

The back section B, consists of a substan-

tially U-shaped frame, pivoted at 1, 1, to the main section A. This frame is preferably formed of angle iron with one flange of the iron horizontal and the other vertical. The horizontal flange, indicated at 5 in the drawings, is preferably cut away near the ends of the arms of the frame from points substantially over the pivots 1 to the ends of the arms. The pivots 1 are located a short distance from the ends of the bars 2, of the main section, and the flanges 5, on the arms of the back section, are adapted to lap over the tops of the bars 2 on the main frame when the back section B is turned down to a horizontal position, as shown in Figure 1 of the drawings, and as shown by full lines in Figure 2. The end portions of the flanges 5, near the pivots 1, with this arrangement, when the back section is turned down to a horizontal position, rest upon the horizontal parts of the bars 2, as shown in Figure 1 of the drawings, and this engagement forms a lock for the back section B, and prevents said back section B from turning down beyond the horizontal position shown by full lines in Figure 2.

The front section C is pivotally connected to the front edge of the main or seat section A, as indicated in Figures 1 and 2 of the drawings. As here shown, this front section is secured to the upper portions of plates 7, preferably by suitable rivets 8, and the plates 7 are pivoted to the front or outer ends of the rails of the main section at 9. As herein shown, the plates 7 are of substantially triangular form, but the shape of the plates is not important and may be varied without departing from my invention.

I prefer to provide the entire frame formed by sections A, B and C with a suitable wire netting or fabric E, preferably provided with the usual tension springs 10. As shown in Figure 1, the edges of this fabric are secured to the frames A, B and C, said fabric permitting the turning of the front and back extensions when it is desired to change the position of the elements of the couch.

The back section B is provided with forwardly extending lugs or extensions 11, and the lower portion of the triangular plates 7 joining the front section C to the main section B, form downwardly extended lugs 13 substantially at right angles to the plane of the said extension.

A connecting rod or link 12 at each end of

the bed is connected at 14 to the end of the lugs 11, and at 15 to the downwardly extending lug 13.

The distance between the pivot point 1 of the back B and the pivot 14, connecting the end of the lug 11 with the rod 12, is substantially equal to the distance between the pivot 9, of the front section C, and the pivot 15 near the end of the lug 13, to which the end of the link 12 is connected.

It will be seen that the lugs 11 to which the links 12 are connected are in line with, or may be said to be in the same plane with, the back section B, while the lugs 13, to which the opposite ends of the links 12 are connected, project at right angles to the plane of the front section C. The result of this arrangement is that when the sections B and C are turned into a horizontal position, as shown in Figures 1 and 2 of the drawing, the portion of the back section B engaging the top of the end portion of the rail 2, prevents said back section from being turned down beyond the horizontal position. When the back section B occupies the horizontal position, shown by full lines in Figure 2, the front section C will be in the horizontal position shown by full lines in Figure 2, and said section C will be locked in this horizontal position. It can not move downward because the rod or link 12, which now extends in the position shown by full lines in Figure 2, locks said front section in its said horizontal position, downward pressure upon the section C being resisted by the straight line thrust from pivot 15 through the link or bar 12 against the pivot 14 at the end of the lug 11. It will, therefore, be impossible to move the front section C out of the horizontal position, shown in Figure 2 of the drawings, until the back section B has been raised, turning upon its pivots 1 and throwing downward the ends of the bars 12 connected thereto, and moving the back section B from the position shown in full lines in Figure 2 to the position shown in dotted lines in the same figure. This motion of the back section B will, through the arms or links 12, turn the front section C from the position shown by full lines in Figure 2 to the position shown by dotted lines in the same figure.

The back section B will now be locked in the position shown in dotted lines in Figure 2, and this section can not be turned down into a horizontal position except by raising the free edge of the front section C, turning said section upon its pivots 9, and bringing the section from the position shown in dotted lines in Figure 2 to the position shown in full lines in the same figure.

I do not limit myself to the details of the construction herein shown and described,

nor do I limit this invention to use upon a couch-bed. It is obvious that the invention may be applied to a chair having a seat portion, and pivoted back and front sections, and I, therefore, include such a chair structure within the terms of the specification and claims herein.

I claim as my invention:

1. The combination, with a couch frame, of front and back sections pivoted thereon and adapted to be adjusted to a horizontal position on a level with said frame for use as a couch, or one section raised to a point above said frame to form a seat-back and the other section lowered below said frame, and links connecting said sections one with the other, the connections of said links with said sections preventing the back section from being lowered until the front section is raised; and preventing the front section from being lowered until the back section is raised.

2. The combination, with a couch frame, of front and back sections pivoted thereon and adapted to be adjusted to a horizontal position on a level with said frame for use as a couch, or one section raised to a point above said frame to form a seat back and the other section lowered below said frame, said back section having extensions beyond its pivots in the plane of the section, said front section having extensions projecting outside the plane of the section, and links pivotally connecting said extensions, the pivots of said back section when lowered taking up end thrust of said links and locking said front section in its raised position, the pivots of said front section in its raised position, and the pivots of said front section when lowered, taking up end thrust of said links and locking said back section in its raised position.

3. The combination, with a couch frame, of front and back sections pivoted to said frame near the top thereof, and adapted to be adjusted to a horizontal position on a level with the top of the frame for use as a couch, the back section being adapted to be turned up to form a seat-back and the front section to be turned down in front of the frame, the back sections having extensions beyond its pivots in the plane of the section, and the front section having extensions opposite its pivots and substantially at a right angle to the plane of the section, and links connecting said extensions, and operating, when the back section is elevated, to lock said section in its upright position, and, when the sections are horizontal, to lock the front section in its horizontal position.

In witness whereof, I have hereunto set my hand this 21st day of March 1921.

EDWARD TURGEON.
